UNITED STATES PATENT OFFICE

BENJAMIN J. TRILLER, OF DUBUQUE, IOWA

DOOR PANEL CONSTRUCTION

Application filed July 5, 1929. Serial No. 376,144.

This invention relates to improvements in garage doors or the like.

It is well-known that large doors such as used for garages or the like, are quite heavy, difficult to handle, and do not properly insulate the chamber with which they are used, and one of the objects of the present invention is to provide a door structure which will eliminate such disadvantages.

Another object of the invention is to furnish a garage door formed mainly of light sheets of insulating material such as "cellotex".

A still further object is to provide a composite door structure which may be readily assembled, and the parts of which will remain in assembled relation indefinitely.

With the foregoing objects outlined and with other objects in view which will appear as the description proceeds, the invention consists in the novel features hereinafter described in detail, illustrated in the accompanying drawings, and more particularly pointed out in the appended claims.

Referring to the drawings,

Fig. 1 is an elevation of a portion of a garage door made in accordance with my invention, and viewed from the inner side thereof.

Fig. 2 is an enlarged vertical sectional view of a detail, taken on the line 2-2 of Fig. 1.

Fig. 3 is a sectional view of a detail, and illustrating the manner of assembling the parts of the door.

Figs. 4 and 5 are sectional views taken respectively on lines 4-4 and 5-5 of Fig. 1.

Fig. 6 is a perspective view, partly in section, of a detail.

In the drawings, the door illustrated is formed of superposed sections 7, 8 and 9, that are pivotally connected together along horizontal lines by means of hinges 10. Section 7 may be of any suitable construction, provided with windows 11, but the sections 8 and 9 are of special construction, to accord with the invention.

Each of these sections 8 and 9 is preferably formed of top and bottom rails 14 and 15 respectively and side stiles 16 into which is assembled, as will be described, a "cellotex"

panel 17 having a thin metal sheet facing 18. This metal facing is on the outside of the door or that side which is exposed to the weather and beside serving as a protection against the elements, lends a strength to the door as well as preventing ready cutting through the "cellotex" panel by an intruder.

To the inner face of the panel 17 is attached, preferably by an adhesive, top and bottom battens 19 and 20 respectively, side battens 21, and center battens 22, all of these being provided with grooves 23, in their faces which contact with the inner face of the panel 17. These grooves are located near the marginal edges farthest removed from their outer edges to receive any excess of glue or adhesive which might be squeezed out from the joints, thereby preventing flowing of the adhesive onto the inner face of the panel to soil the same.

On the outside of each door section, wherever a center batten 22 occurs, is provided a muntin 24, the same being seated within a groove 25 provided in the outer face of the panel 17, the muntin and panel preferably not being secured to each other. The metal sheets 18 abut the sides of the muntin 24 and are overlapped on the outside by lateral extensions 26 formed on the muntins at each side thereof.

The edges of the top and bottom rails 14 and 15 and of the side stiles which receive the panel 17 are specially formed to provide a compound curved or ogee surface 27, shoulder 28, beveled surface 29, shoulder 30, plain surface 31, inclined or wedge surface 32, and face 33. The shoulder 28 and surface 29 make up a wedge shaped groove, while the shoulder 30, the surfaces 31 and 32 make up another wedge-shaped groove. The upper and lower ends of the side stiles are shaped to conform to that of the especially formed edges of the top and bottom rails by having a compound curved or ogee surface 37, face 38, beveled edge 39, face 40, edge 41, inclined or wedge face 42, and face 43. The parts 37 to 43 inclusive engage with the parts 27 to 33 inclusive, respectively, when the rails and stiles are assembled into a frame, and the

joint between them is reinforced by dowels 45 throughout.

The upper and lower ends of the muntins are also specially formed to provide compound curved or ogee surfaces 57 which conform to and abut the surfaces 27 of the top and bottom rails. The side edges of the muntin-extensions 26 may also be of ogee formation, but this forms no part of the invention, and is not illustrated. They are also provided with projections, the faces 58 and 59 of which engage with the faces 28 and 29 of the top and bottom rails. The faces 27 and 28 of the rails 14, and 15 and stiles 16 are at an acute angle to each other and form a rib that is received between the faces 57 and 58 which form notches in the ends of the muntins. Thus it will be seen that the muntins, not being attached to the panels 17, but being loosely located in the groove 25 of the panels are prevented by the wall of said groove from lateral and rearward displacement, and from forward displacement by the projecting face 58 engaging behind the shoulder 28 of the top and bottom rails. Rearward displacement is also prevented by the contacting beveled surfaces 29 and 59.

In constructing the door sections, the panel 17 have the battens 19, 20, 21 and 22 secured to them, preferably by an adhesive as in the manner described, though by nailing may in some cases be contemplated. The center battens have their upper and lower ends shaped to conform to the contour of the top and bottom battens in order to produce the miter effect 65, though this effect may be produced otherwise. With the battens applied the panel and battens are subjected to the action of an edging tool, which uniformly produces the surfaces 49, 50, 51 and 52 and the parts are then ready for assembling.

Assembling is accomplished in a standard door press which is not illustrated, the parts being laid upon the press bed or table 66 as is illustrated in Fig. 3 with the metal sheets 18 loose upon the top of the panel 17, and the panel 17 with its attached battens 19 and 21 resting upon the table 66. The press is then put into operation moving the top and bottom rails 14 and 15 against the ends of the side stiles 16 and the stiles 16 toward each other, during which movement the wedge surface 52 ride up the wedge surfaces 32 causing the entire panel 17 with its metal facing 18 and attached battens to lift from the table 66. This lifting action continues until the parts are entirely together, at which time the sheet metal facing 18 will be securely bound against the shoulders 28 of the rails 14 and 15 and stiles 16. In cases where the sheet metal facing 18 is not employed, the panel 17 itself engages the shoulders 28 tightly to produce a substantially watertight joint. It will be observed that the

clamping action upon the panel unit is between the shoulders 28 and the wedge surfaces 32 of the rails and stiles, and that because of the yielding nature of the material composing the panel 17, the joints between the rails 14 and 15 and stiles 16 will always be permitted to close, since if the panel comes into contact with the shoulders 28 before the said joints are closed, the compressibility of the panels 17 will permit further movement until the rails and stiles meet in proper joining fit.

It will be observed that in assembling, the metal sheets 18 are merely laid upon the panel 17 and since these sheets have more or less buckle portions thereof especially at their edges will extend away from the panel. This makes it necessary that the panel 17 and metal facing 18, during assembling, shall be moved against the shoulder 28 with a movement more or less perpendicular thereto, while the rails 14 and 15 and stiles 16 are being closed against the edges of the panel parts. Any attempt to assemble the panel with its sheet metal facing by moving it directly into the rail and stile groove with a direct edgeways movement would result in the sheet metal striking the edge of the ogee surface 27, and even without the sheet metal facing being present, this would also occur with the panel 17 which also has more or less buckle.

Having thus described my invention, what I claim as new and desire to secure by Letters Patent is:

1. In panel construction, the combination of a sectional grooved frame and a panel member inclosed thereby, one wall of the frame groove being beveled, and the panel member being engaged only with said beveled wall when the parts are juxtaposed prior to assembly, said beveled wall serving to move one face of the panel member against an opposite wall of the frame groove when the frame sections are moved toward the panel member during assembling, the panel member including a compressible felted fibre portion which permits the frame joints to close even after the panel member has engaged the said opposite groove wall.

2. In a door construction, the combination of a sectional grooved frame having a surface at an acute angle to one wall of said groove forming a rib, a muntin having its ends notched to receive said rib, a panel member having one of its faces engaged with said rib, the opposite face of the panel member having beveled engagement with the other wall of said frame groove.

3. In a door construction, the combination of a sectional grooved frame having a surface at an acute angle to one wall of said groove forming a rib, a muntin having its end notched to receive said rib, a panel member having one of its faces engaged with said

rib, the opposite face of the panel member having beveled engagement with the other wall of said frame groove, the panel member being grooved and receiving the muntin in said groove.

4. In a door construction, the combination of a sectional grooved frame having a surface at an acute angle to one wall of said groove forming a rib, a muntin having its end notched to receive said rib, a panel member having one of its faces engaged with said rib, the opposite face of the panel member having beveled engagement with the other wall of said frame groove, the panel being of a compressible nature to permit the frame joints to close during assembling even after the panel has engaged said rib.

5. In a door construction, the combination of a sectional grooved frame having a surface at an acute angle to one wall of said groove forming a rib, a muntin having its end notched to receive said rib, a panel member having one of its faces engaged with said rib, the opposite face of the panel member having beveled engagement with the other wall of said frame groove, the panel member being grooved and receiving the muntin in said groove, the panel being of a compressible nature to permit the frame joints to close during assembling even after the panel has engaged said rib.

6. A door comprising a sheet of fibrous insulating material, top, bottom and end battens secured to the edge portions of said sheet and having wedge shaped projections, center battens secured to one side of the sheet, a muntin on the opposite side of the sheet, the center battens having their ends engaging the top and the bottom battens, cross rails and side stiles having wedge shaped grooves into which the wedge shaped projections extend, other grooves in the cross rails and side stiles into which the edge portions of the sheet extend, the ends of the muntin also extending into the last mentioned grooves.

7. In panel construction, the combination of a sectional grooved frame and a panel member enclosed thereby, one wall of the frame groove being beveled and opposing two offset walls of the groove which latter offset walls are substantially parallel with the plane of the frame, the panel member comprising two united layers one of which is of relatively high compressibility and of greater thickness than the distance between

the two said offset walls and the other of which is of relative negligible compressibility and having a beveled face, said beveled face being engaged only with said beveled wall of the groove when the parts are juxtaposed prior to assembly and said beveled face and beveled wall serving to move one face of the relatively highly compressible layer against the outer of said offset walls of the groove when the frame sections are moved toward the panel member during assembling, the relatively highly compressible layer being compressed to permit the frame joints to close even after the said relatively highly compressible member has engaged the said outer offset wall of the groove.

8. In panel construction, the combination of a sectional grooved frame, a compressible panel of substantially uniform thickness, battens of relatively non-compressible material surrounding and secured to the panel and having an outer beveled face, the combined thickness of the panel and batten at the extreme outer edge of the panel being less than the distance between opposite walls of the frame groove and the thickness of said parts increasing toward the center portion of the panel to a degree that when the joints of the outer frame are entirely closed the compressible panel will be compressed at its edges between the battens and one wall of the frame groove and the battens will be engaged with one wall of the groove.

9. In panel construction, the combination of a sectional grooved frame, one of two opposite walls of the groove being beveled, a compressible felted fibre sheet and a metal sheet forming a panel, wooden battens surrounding and secured to the panel and having an outer beveled face, the combined thickness of the metal plate, fibre sheet and batten at the extreme outer edge of the panel being less than the distance between the beveled and opposite walls of the frame groove and the thickness of said parts increasing toward the central portion of the panel to a degree that when the joints of the outer frame are entirely closed the compressible sheet will be compressed at its edges between the batten which then engages the beveled wall of the frame groove and the metal sheet which engages the opposite wall of the frame groove.

BENJAMIN J. TRILLER.
